EDGAR M. WILCOX AND McCORMACK C. McPHERSON, OF HAMMOND, INDIANA

CAR-VENTILATING SYSTEM

Application filed September 16, 1928. Serial No. 135,738.

Our invention relates to improvements in ventilating systems for cars, and more especially to a type adapted to supply fresh air at a temperature which will maintain the temperature in a car always substantially constant.

To this end, our invention embodies a system comprising an air intake, an air conveying passage, together with an air circulating means, and provided with a coil interposed between the air circulating means and the air passage, which coil is adapted to serve either as a heating coil, as, for instance, a radiator connected to a steam supply or, as a cooling coil, such as, for example, an expansion coil of a refrigerating system. We have provided suitable connections for connecting the ends of the coil with either a source of steam, such as a regular steam line from a locomotive boiler, or for connecting the ends of the coil to a suitable refrigerating plant of a type to be carried by a railroad car and to be driven by any suitable means as, for instance, through a mechanical connection from the railroad car axle. These pipe connections are provided with suitable cut-off valves placed adjacent the connection with the coil in order that either one of the systems may be selected for operation without in any way influencing the other system or the pipe connections therefor, the supply pipe for the refrigerating system being provided adjacent the cut-off valve with the expansion valve which, when taken together with the coil, constitute the necessary expansion coils for a refrigerating system of the type employed.

A single automatic control means has been provided which is adapted to be selectively connected to either one of the two systems, the control means comprising a thermostat which, when connected with the steam supply, controls a throttle positioned within the steam supply pipe in a manner to pass or obstruct the passage of steam, permitting such an amount to reach the coil as will cause the temperature within the car to be maintained within a predetermined range of temperature. In the event that the thermostat is connected to the refrigerating system, variations in the temperature within the car

within a predetermined range will, through suitable electrical connections, influence a magnetically operated belt-tightener, which belt-tightener being interposed between the driving axle and the driven wheel of the refrigerating plant will cause the driving influence of the car axle to be automatically clutched in and out as a source of power, and thereby cause the refrigerating plant to operate and in turn to cool the coils more or less according to the temperature already existing in the car, the operation always being such as to counteract any variations in temperature due to outside atmospheric conditions.

One of the objects of our invention is to provide a circulating system for railroad cars which will supply fresh air to the interior of a car, the temperature of which has been previously established so as to maintain the temperature of the car substantially constant for all seasons of the year.

Another object of our invention is to provide a ventilating system for railroad cars in which is provided a coil interposed in the circuit of air, which coil is adapted for use either as a heating coil or a cooling coil, together with suitable connections for selectively connecting the coil with a steam supply or a refrigerating system.

Another object of our invention is to provide a ventilating system for railroad cars embodying the advantages of the above stated objects together with a single control means operable upon temperature conditions, and which is of a type suitable to control a steam throttle, as when connected to operate in conjunction with the heating system, or to control a magnetic belt-tightening clutch in a manner to influence the capacity of a refrigerating system, and in both of these instances, influencing each of the control means an amount which will cause the operation of each of the separate systems as a result to be such, that the temperature in the car is maintained within a predetermined range regardless of which of these systems is connected for operation.

These and other objects are accomplished by means of the arrangement disclosed on

the accompanying sheet of drawings, in which—

8 Figure 1 is a side elevation of a railroad car equipped with our improved ventilating system, the showing being partly in cross-section and partly diagrammatic, the coils being shown in perspective;

10 Figure 2 is a plan view, partly in cross-section of the air passage disclosing the ventilating openings and the relationship of the coil to the entrance of the air passage; and

15 Figures 3 and 4 are enlarged views in perspective of two of the ventilating openings, disclosing the air deflectors which are of unequal height, the two showings in these figures representing the openings at the opposite ends of the air passage, the highest air deflector being positioned at the outlet end of the air passage.

20 The various novel features of the invention will be apparent from the following description and drawings, and will be particularly pointed out in the appended claim.

25 Referring to the figures of the drawings, it will be noted that our ventilating system is adapted to be applied to a railroad car 10, provided with an air intake through its top and at one end, such as shown at 11. Positioned in the top of the car on the inside is an elongated housing 12 having flared ends 13, one of which is adjacent the air intake, the opposite end being provided with shutters 14 to form a suitable adjustable outlet. Interposed between the air intake and the 30 mouth of the air passage is the air circulator 15, preferably of the fan type, which is electrically operated from any suitable source of current such as, for instance, the lighting system storage battery already provided on railroad cars, the circulating action being supplemented by a similar fan 16 positioned in the outlet end of the passage, which fan is of the "pulling" type.

35 Between the mouth of the air passage and the circulating means, coils 17 are placed so as to receive a current of air from the intake and to present a large surface thereto in a manner to influence the temperature thereof. One end of the coil is connected to a pipe 18 which is in turn connected to a supply of steam, such as the main steam line from a locomotive, the opposite end of the coil being connected to a similar pipe which serves as a return to the steam system, this last-named 40 pipe being omitted in the drawings. Positioned in the pipe 18 adjacent the connection to the end of the coil is a cut-off valve 19 and further removed therefrom, is a throttle 20 which is connected with a thermostatic control through the electrical connection 21 so as to be influenced by the thermostat 22. The coil is also connected to the refrigerant intake pipe 23, provided with a shut-off valve 24 and an expansion valve 25, the pipe extending down the side of the car and being

5 attached at its other end with a mechanically driven refrigerant compressor, designated generally at 26. This system also has a return pipe, shown at 27, establishing communication between the opposite end of the coil and the intake for the compressor. The compressor with the cooling coils 28 and the expansion valve constitute the elements of a refrigerating plant of an ordinary type, the cooling coils serving to reduce the temperature of the compressed medium heated under the influence of compression. The compressor is driven by a belt, such as shown at 29, from the car axle, the belt being of a size which will ordinarily permit slipping between the driving and driven elements, sufficient tautness being effected by the belt-tightener 30 magnetically controlled by suitable mechanism, represented at 31, and influenced through suitable connections, such as shown at 32, from the thermostat 22, above referred to, the switch 33 being provided in order that the thermostat may selectively control the heating throttle 20 or the magnetic belt-tightener 31.

55 In order to prevent any possibility of steam in one case from entering the refrigerating system, or refrigerant in the other case from entering the heating system, a second cut-off valve is provided in each system, designated 34 and 35 respectively.

60 In the air passage, positioned in the upper portion of the car, are placed ventilating openings through the bottom wall thereof in a manner to cause the uniform distribution of the circulated air throughout the entire length of the car, each opening being provided with a screen 36 and an upstanding air deflector 37 adapted to intercept the current of air and direct same downwardly through the opening. The air openings are provided with deflectors of different sizes, the one nearest the intake being smallest, the others successively increasing in height so as to provide the more uniform distribution of air, this arrangement permitting an ample supply at the end remote from the intake.

65 In operation, the circulating fans 15 and 16 are started causing a current of air to be drawn in through the intake 11, and forced over the coil 17 and through the air passage 12, a portion thereof being deflected through each of the air openings and into the respective portions of the car throughout its length. Depending upon the season of the year, either 70 the steam system or refrigerating system is connected to the coil in a manner to either raise the temperature or to lower the temperature to that desired to be maintained in the car or it may be that the outside temperature is the same as that desired in which event no heating or cooling would be effected. In the event the steam system is to be connected, valves 24 and 35 are shut off and the valves 19 and 34 are opened in a manner to permit 75

the supply of steam from the main steam line of the train to enter the coil through pipe 19, in which instance the coil acts as a radiator to elevate the temperature of the air as drawn in from the outside. In this case, the switch 33 is connected in the manner shown in Figure 1 so that the thermostat 22 influences, through the electric connection 21, the throttle 20, thereby regulating the passage of steam at 20, the passage of steam being such that for every degree of change in temperature as registered at the thermostat the heating of the coil 17 will be an amount sufficient to counteract the temperature difference found in the car.

When it is desired to connect the refrigerating system, as for instance, in the summer time when the outside atmospheric temperature is above that desired to be maintained in the car, valves 19 and 34 are shut off and valves 24 and 35 are opened. The belt-tightener 30, which is capable of being set to idle, is positioned in a manner to tighten the belt 29, thereby causing the rotation of the car axle to set the refrigerating plant in operation, which acts to supply through the pipe 23 condensed refrigerant which has been cooled in its condensed state, to the expansion valve 25 which valve permits the refrigerant to expand in the coil 17 with a great absorption of heat and to return to the compressor through pipe 27. In this case, the thermostat 22 is also employed, the switch 33 being moved to the opposite terminal in a manner to cause magnetic clutch 31 to be influenced electrically according to the temperature differences found in the railroad car. Here also the electrical influence on the belt-tightener, for every degree of temperature change as registered at the thermostat, is such that the drive of the refrigerant compressor is influenced to cause the compressor to pump a greater or less amount of refrigerant which amount is exactly sufficient to cause the coils to cool the incoming air to an extent to counteract the difference in temperature found in the car. In the event the outside temperature is exactly that which is desirable for the inside temperature, the incoming air will be forced into the car without treatment for temperature, by virtue of the fact that the thermostat control will so influence the system to which it is connected as to prevent any action thereof, within that particular range found in the car.

During the operation of this system, whether it be in conjunction with the heating or cooling systems, an absolutely uniform distribution of air throughout the length of the car is assured by the type of air deflectors employed, namely by providing air deflectors of successively increasing heights according to the degree of remoteness from the intake, and further, the general circulating effect of the fans may be regulated as a whole by shut-

ters 14 which may be closed to a variable extent at which time the air is forced into the intake by the circulator 15, and permitted to pass directly through the air passage a greater or less amount, so as to influence the amount passing into the car.

We claim:

A car ventilating system comprising in combination, means for circulating a current of fresh air, a coil located in the path of the circulated air for controlling the temperature thereof, a source of steam and means having a shut-off valve for connecting said source of steam to said coil, a refrigerating plant and means having a shut-off valve for connecting said refrigerating plant to said coil, electrically responsive means for controlling the supply of steam and electrically responsive means for controlling the capacity of said refrigerating plant and a single thermostat adapted to control either of said electrically responsive means and means for selectively connecting said thermostat to one or the other of said electrically responsive means.

Signed at Hammond, Indiana, this 13th day of September, 1926.
